UNITED STATES PATENT OFFICE

HANS P. DAHLSTRAND, OF WAUWATOSA, WISCONSIN, ASSIGNOR TO ALLIS-CHALMERS
MANUFACTURING COMPANY, OF MILWAUKEE, WISCONSIN, A CORPORATION OF
DELAWARE

ROTOR STRUCTURE

Application filed May 5, 1930. Serial No. 449,780.

This invention relates to a means for maintaining the centering of a supporting or ring member, such as the blade carrying element of a steam turbine, on a supporting shaft. 6 The high speeds at which these turbines operate cause a corresponding amount of centrifugal force to be acting on the material of which the ring members are made. The diameter of the ring member increases with the 10 speed due to the increased stress. Consequently, the ring members had to be heated and shrunk onto the shaft in order that a rigid operative connection might still be had at the working speeds of the turbines. This 15 invention dispenses with the necessity of heat treating the ring member and by merely providing a resilient element that is secured to the shaft at one end and that engages with the ring member at the other end to have a 20 centered ring member at all working speeds.

On the drawing a pair of ring members is shown mounted in contacting relation on a shaft of different diameters.

On the drawing 2 is the shaft; 3 and 4 the 25 ring members; 5 and 6 the ring elements; 7 the keys for locking the ring members to the shaft; 8 and 9 are the shoulders on the shaft; 10—10 are the turbine blades; 11 is the abutment or annular flange on the ring element; 30 12 is the bore or internal diameter of the ring element; 13 the tubular portion of the ring element and 14 the bore of the ring member.

In order to avoid the expense incidental to 35 and danger in heating a ring member to shrink same onto a shaft that is to be rotated at high speeds, the applicant has invented the new and novel means for maintaining the centering of such a member, referred to above and now about to be more fully described.

While two ring members are shown in contacting relation on the drawing it is not necessary that they be so related nor that a plurality be mounted on a shaft. The drawing 45 illustrates the invention used in connection with a steam turbine in which compactness and saving in space are of utmost importance. For sake of simplicity the invention will be described as used with a shaft of uniform 50 diameter.

As seen from the drawing, 4 may be any form or kind of a ring member of considerable mass and it may be keyed by a key 7 to a shaft 2 so as to be drivingly connected therewith. It will of course be understood that the invention is not limited to the shown key and slot means for effecting the driving connection between the massive ring member and the shaft but any other suitable means may be used to accomplish this connection. 55

Since the invention dispenses with the necessity of shrinking the ring member onto the shaft, the bore of the ring member may be of the same diameter as that of the shaft or even of a slightly larger diameter. The 60 bore of the ring member as shown is, however, not of a uniform diameter for reasons which will be presently stated.

6 is a ring element preferably of a material having a high elastic limit. Spring 70 steel would be an ideal material from which to make such rings. The principal feature of the invention is to anchor or cause an interlocking relation between the outer periphery of the ring element and the ring member while the inner periphery of said element firmly grasps the shaft so as to form a rigid connection therewith.

The anchoring or interlocking relation between the said element and member may be obtained by providing the radially directed flat portion of the ring element with a suitable flange or abutment 11 that is received in an annular groove, not numbered, in the ring member. 75

80 It is apparent that the ring element might be formed so as to have a flat portion just referred to and the flange or abutment 11, with the inner peripheral portion thereof in firm grasping contact with the shaft along a circumferential line that is not on the surface of the shaft that is embraced or surrounded by the ring member. 85

However, in order to save space applicant has designed the ring member so that the inner periphery of the ring element firmly grasps the surface of the shaft along a circumferential line that is on the surface of the shaft surrounded by the ring member. The ring element therefore is formed so as 90 95 100

to have a tubular portion extending from the flat or disk portion thereof in the same direction as the abutment or flange 11. The length of said tubular portion as shown may 5 be considerably greater than the length of the key receiving slot provided in the ring member. In order that the described point 10 of contact between the inner periphery of the ring element and shaft be had, the ring member 4 is provided with a bore of two different diameters the larger bore portion providing the space in which the tubular portion of the ring element is received. It is preferable that the ring element be provided with an annular flange that forms the surface of contact between the ring element and the shaft. Since the ring element may be shrunk fit on the shaft, the diameter of the bore 12 of the annular flange, not numbered, may be made less than the diameter 20 of the shaft.

On the drawing 10 represents turbine or fan blades that may be carried by a massive ring member 4 rotating at high speeds in 25 connection with which the invention is to be used.

The operation of the device is as follows. When the massive ring member 4 is rotating at high speed there is set up therein a 30 corresponding centrifugal force. This subjects the material of which the ring member is made to a considerable stress which acts so as to enlarge the bore of the ring member and the member becomes uncentered. With 35 the ring element 6 as described engaging the ring member, it remains centered with respect to the shaft over all operating speeds thereof even though they be high.

It should be understood that it is not desired to limit the invention to the exact details of construction herein shown and described, for various modifications within the scope of the claims may occur to persons skilled in the art.

45 It is claimed and desired to secure by Letters Patent:

1. In combination, a supporting shaft, a relatively flexible ring element having one portion rigidly associated with said shaft and having an abutment surface remote 50 from said shaft and facing the same, and a relatively stiff and heavy ring member positively connected directly to said shaft independently of said ring element and engaging 55 said surface.

2. In combination, a rotary support, a flexible ring element rigidly attached to said support and having an abutment surface spaced from said support and facing the 60 axis thereof, and a relatively stiff and heavy ring member engaging said surface, said member being drivingly connected directly and independently of said ring element with said support.

65 3. In combination, a rotary element, a rel-

atively massive member embracing and drivingly associated with said element, and a relatively resilient centering element snugly fitting and firmly secured to said rotary element and having an annular surface facing 70 the axis of said rotary element and embracing a corresponding annular surface of said member, the driving association of said massive member with said rotary element being independent of said resilient centering element. 75

4. In combination, a rotary support, a massive ring member mounted on said support so as to have a driving connection therewith, and a relatively resilient centering ring having annular flanges at its outer and inner peripheral portions, the outer one interlocking with the ring member and the inner one being rigidly attached to said support, the driving connection of said massive member with said support being independent of said resilient centering ring. 80

5. In combination, a rotary shaft, a ring member mounted on said shaft so as to have a driving connection therewith, and a relatively resilient centering ring having annular flanges at its outer and inner peripheral portions, the outer flange being received in an annular groove isolated and spaced from the shaft and provided in the ring member and the inner flange snugly fitting and being firmly secured to the shaft, the driving connection of said member with said rotary shaft being independent of said centering ring. 85

6. In combination, a rotary shaft, a massive ring member mounted on said shaft so as to have a driving connection therewith, and an L-shaped relatively flexible ring element having two annular flanges, one of said flanges being directed toward and firmly pressing against said shaft and the other flange being received in an annular groove isolated and spaced from the shaft and provided in said ring member, the driving connection of said massive member with said rotary shaft being independent of said flexible ring element. 90

7. In combination, a rotary shaft, a massive ring member mounted on said shaft so as to have a driving connection therewith, said member having a bore of different diameters, one portion of said bore closely approximating the diameter of the shaft while the other portion is of a larger diameter, a relatively flexible ring element snugly fitting said shaft, and having one part thereof positioned in the space between the shaft and the wall of the bore of greatest diameter and connected with the ring member through another part of said element, to restrain outward displacements of said ring member in a plurality of radial directions. 95

8. In combination, a rotary shaft, a ring member mounted on said shaft, said member having a bore of different diameters, one por-

tion of said bore closely approximating the diameter of the shaft and cooperating to provide a driving connection between said massive member and said rotary shaft, the other portion of said bore being of a larger diameter, a relatively resilient ring element rigidly connected to said shaft, and having one part thereof positioned in the space between the shaft and the wall of the bore portion of greatest diameter, and firmly secured to the ring member through another part thereof, to restrain outward displacements of said ring member in a plurality of radial directions.

9. In combination, a rotary shaft, a ring member mounted on said shaft so as to have a driving connection therewith, means for forming said driving connection, and a relatively resilient centering ring having a tubular portion and a disk portion, the tubular portion firmly grasping said shaft and the disk portion being provided with means cooperating with said ring member, for effecting an outwardly coupled connection between said centering ring and said ring member.

10. In combination, a rotary shaft, a ring member having a shaft receiving bore of different diameters, a relatively resilient centering ring having a part closely surrounding the shaft and received within a space bounded by said shaft and the wall of the bore portion of greater diameter, said centering ring further having a part located exteriorly of said space and engaging said ring member, and means forming a driving connection between said ring member and said shaft.

11. In combination, a rotary shaft, a ring member having a shaft receiving bore of different diameters, a resilient centering ring having a part closely surrounding and rigidly secured to said shaft and received within a space bounded by said shaft and the wall of the bore portion of larger diameter, said centering ring further having a part located exteriorly of said space and inwardly engaging said ring member, and means forming a driving connection between said ring member and said shaft, said means being located contiguous to the lesser diameter bore portion of said ring member.

50 In testimony whereof, the signature of the inventor is affixed hereto.

HANS P. DAHLSTRAND.
